OSCILLATING DEVICE ACTIVATED BY
BIMETALLIC ELEMENT

Francis M. Lyons, Oceanside, N. Y., assignor to
Einson-Freeman Co., Inc., Long Island City,
N. Y., a corporation of Delaware

Application January 23, 1953, Serial No. 332,797

2 Claims. (Cl. 60—23)

1

My present invention relates generally to motors, and has particular reference to a motive unit which generates oscillatory movements as the result of distortion of a bi-metallic element whose opposite surfaces are subjected to different temperatures at successive intervals of time. Coordinately, my invention relates to oscillating devices in which the driving motor is of the character mentioned.

A general object of the invention is to improve the efficiency of operation of a type of motive unit that affords a simplified and unusually inexpensive source of relatively minute motive power suitable for such uses as the animation of light-weight advertising displays, amusement devices, and similar items. The type of motor to which the invention relates derives its energy from an activator having a temperature appreciably different from the ambient temperature, the temperature differential being utilized by means of the distortions of a bi-metallic element. This element is of the well-known type whose opposite surfaces have different temperature coefficients of expansion.

More particularly, the motor involves a resilient deflectable strip secured in association with the activator in such a way that one end of the strip is anchored at a point of pivotal support while the strip extends in an adjacent relation to the activator. The strip includes as a part thereof a bi-metallic element adapted to distort upon subjection of its opposite surfaces to the two different temperatures which are thus afforded. The distortion is effective to initiate a swinging movement of the strip away from the activator, and it is during this swing that the bi-metallic element is afforded an opportunity to resume its normal shape, so that upon the completion of the return swing the activator is again effective to distort the bi-metallic element and thereby repeat the operation.

In the preferred embodiment of the invention, the source of temperature differential is an ordinary electric lamp of relatively low wattage. The heat generated by such a lamp is quite small but is nevertheless sufficient for the present purpose. Where the motor is to be used for the animation of advertising displays such as the cardboard devices commonly employed on store counters and in store windows, the use of an electric lamp as the source of temperature differential is of particular advantage because it can be utilized at the same time to illuminate a selected part of the display. It has been found, however, that the

2

heat radiated by such a lamp often warms up the surrounding region to such an extent that the desired cooling-off of the bi-metallic element does not occur as quickly and reliably as it should, the smooth and efficient operation of the motor being correspondingly impaired. It is the object of the present invention to overcome this difficulty.

In accordance with my invention, an opaque heat-conductive shield is interposed between the lamp and the bi-metallic element. The shield is heated by the lamp, and is so positioned that the bi-metallic element establishes contact with it, and is heated by it, on each return swing. At the same time, the shield serves as a barrier to the transmission of radiant heat from the lamp to the space in which the movements of the bi-metallic element take place.

The preferred way of achieving the objectives and advantages of the invention is illustrated in the accompanying drawing, in which—

Figure 1 is an elevational view of the working parts of an illustrative oscillating device constructed in accordance with the present invention;

Figure 2 is a view taken at right angles to Figure 1; and

Figure 3 is a perspective view of the opaque heat-conductive shield, shown by itself.

In the device shown, 20 represents an ordinary electric lamp, having a relatively low wattage such as 60 watts or so, mounted in an ordinary lamp socket 21. The socket may be secured in any suitable fashion to a supporting bracket 22 by means of which the lamp is mounted in appropriate association with a display or other oscillating device in connection with which it is to be used.

Secured to the bracket 22, by rivets 23 or any equivalent mounting expedient, is a resilient deflectable strip which extends upwardly in adjacent relation to the lamp 20. As indicated and suggested in the aforementioned pending patent application of Brett S. Nichols, this strip may be constructed in various ways. I have chosen to show the strip formed of a lower springy metallic element 24, an intermediate bi-metallic strip 25 of well-known distortable character, and an upper segment 26. These parts are secured together in any convenient manner and the element 25 is so shaped and positioned that it normally lies in close proximity to the lamp 20. The two metals of which the element 25 is formed are so arranged with respect to the lamp that the heat from the lamp will distort the element to initiate a swing-

ing movement of the entire deflectable strip away from the lamp.

For illustrative purposes I have shown an element 27, forming part of an advertising display device, secured to the free end of the segment 26. The element 27 may be composed of a blank of cardboard or the like, and may have an appropriate cardboard loop 28 formed on it by means of which it is frictionally supported upon the free end of the segment 26. The element 27 constitutes a "load" which is so designed, in relation to the shape and disposition of the deflectable strip on which it is mounted, that an oscillation of substantial magnitude may be achieved. In the illustrated construction, the parts are intended to swing back and forth between the full-line and the dotted-line positions. More specifically, the center of gravity of the "load" is so located that when the bi-metallic element 25 is distorted under the influence of the lamp 20 the center of gravity moves past the dead center axis extending vertically through the point of pivotal support.

In accordance with my invention, there is interposed between the lamp 20 and the bi-metallic element 25 a shield which is heat-conductive and which is heated by the lamp, yet opaque to the radiant energy emanating from the lamp. Where the lamp is of the ordinary shape shown, provided with a filament and a substantially globular glass filament enclosure, the shield can be conveniently formed of a strip of metal 29 bent into the shape of an inverted-U. Such shield is shown by itself in Figure 3. It is made of a size and shape permitting it to be applied directly to the lamp, as shown, and to retain its position in direct contact with the lamp by frictional engagement. To achieve this result, it is satisfactory to impart to the strip 29 a curvature substantially equal to that of the lamp, and to form the strip of a metal which is slightly springy, the free ends of the strip being turned toward each other to a slight degree as shown. As a result, the shield 29 can be applied endwise to the lamp bulb and will remain in the position shown as a result of its inherent resilience.

When the lamp is turned on, the bulb becomes heated in well-known fashion. This heat is transferred to the metal shield 29, and quickly brings about a distortion of the bi-metallic element 25. The parts are so designed that the distortion is effective to move the center of gravity past the dead center axis, and as this happens the weight of the load amplifies the swinging movement that has been initiated. Depending upon the size, shape, resilience, and other characteristics of the deflectable strip and of the load itself, the swinging movements will reach an extreme position shown in dotted lines at which the stress upon the element 24 is sufficient to impart a returning impulse. Affecting this result is the retarding action of the additional spring 30 which may be provided near the pivotal support, as shown. As the parts tend to resume their initial positions, the center of gravity returns across the dead center axis and becomes effective to complete the return swing. In the meantime, the bi-metallic element 25 has had an opportunity to return, at least partly, to its initial undistorted shape, and the process is repeated as the element 25 comes again into contact with the heated shield 29.

Because of the fact that the shield 29 serves as a barrier to the transmission of radiant heat from the lamp to the space in which the movements of the bi-metallic element 25 take place,

the air in this ambient region does not become overheated, and is always cool enough to permit the bi-metallic element 25 to cool off to the desired degree during the time that it is out of contact with the heated piece of metal 29. Because of this, the operation of the motor is uniform, efficient, and reliable at all times.

The motor is unusually small in size and has a minimum of moving parts, requiring no lubrication or other attention. It will operate almost indefinitely at a negligible cost of operation.

It will be understood that a wide variety of oscillatory movements may be provided for, differing in range of swing, relative speeds of advance and return, and other qualities whose variation may be desirable to achieve different effects. The "load" imposed upon the swinging strip may itself constitute the display element or other object whose oscillation it is desired to accomplish, or the motor may be hooked up in simple fashion to a connecting rod or link by means of which the oscillatory movements of the strip may be transmitted to a relatively remote point.

The particular design of the deflectable strip, of the bi-metallic element forming part of it, and of extraneous springs optionally employed, such as the spring shown at 30, will depend upon the nature and characteristics of the oscillation that may be desired in any particular case.

In general it will be understood that those skilled in the art will be enabled to modify the details herein described and depicted without necessarily departing from the spirit and scope of the invention. It is intended, therefore, that these details be considered as illustrative, not in a limiting sense.

Having thus described my invention and illustrated its use what I claim as new and desire to secure by Letters Patent is:

1. An oscillating device of the kind described, comprising an electric lamp, a resilient deflectable strip secured at its lower end to a point of pivotal support and extending upward therefrom in adjacent relation to said lamp, said strip including as a part thereof a bi-metallic element so shaped and positioned that the heat of the lamp is effective to distort it and by such distortion to initiate a swinging movement of the strip away from the lamp, a load carried by the free end of the strip and having its center of gravity so located that as the strip moves under the influence of said distortion the center of gravity is carried past the dead center axis which extends vertically through said point of support, thereby amplifying the swinging movement away from the lamp, and an opaque heat-conductive shield heated by said lamp and fixedly positioned between said lamp and said bi-metallic element so that the latter establishes contact with and is heated by said shield on each return swing, said shield serving as a barrier to the transmission of radiant heat from the lamp to the space within which the movements of the bi-metallic element take place.

2. An oscillating device of the kind described, comprising an electric lamp including a substantially globular filament enclosure, a resilient deflectable strip secured at its lower end to a point of pivotal support and extending upward therefrom in adjacent relation to said lamp, said strip including as a part thereof a bi-metallic element so shaped and positioned that the heat of the lamp is effective to distort it and by such distortion to initiate a swinging movement of the strip away from the lamp, a

load carried by the free end of the strip and having its center of gravity so located that as the strip moves under the influence of said distortion the center of gravity is carried past the dead center axis which extends vertically through said point of support, thereby amplifying the swinging movement away from the lamp, and a heat-conductive piece of metal heated by said lamp and so positioned between said lamp and said bi-metallic element that the latter establishes contact with and is heated by said metal on each return swing, said metal being

a U-shaped piece frictionally engaging around the globular lamp filament enclosure and serving as a barrier to the transmission of radiant heat from the lamp to the space within which the movements of the bi-metallic element take place.
